UNITED STATES PATENT OFFICE

163,703

SPOON OR SIMILAR ARTICLE

Leon Roy Lehman, Terre Haute, Ind.

Application April 10, 1950, Serial No. 9,102

Term of patent 14 years

(Cl. D44—29)

To all whom it may concern:

Be it known that I, Leon Roy Lehman, a citizen of the United States, and residing in the city of Terre Haute, county of Vigo, and State of Indiana, have invented a new, original, and ornamental Design for a Spoon or Similar Article, of which the following is the specification, reference being had to the accompanying drawings, forming a part hereof.

On the drawings:

Fig. 1 is a top plan view of a spoon, showing my new design.

Fig. 2 is a side elevation of said spoon.

Fig. 3 is a bottom plan view of said spoon.

I claim:

The ornamental design for a spoon or similar article, substantially as shown.

LEON ROY LEHMAN.
